UNITED STATES PATENT OFFICE.

ROY M. WARBERG, BERNHARD ANDERSON, AND FRANK ANDERSON, OF CHICAGO,
ILLINOIS.

COSMETIC-POWDER DISPENSER.

Application filed March 5, 1925. Serial No. 13,038.

To all whom it may concern:

Be it known that we, ROY M. WARBERG, BERNHARD ANDERSON, and FRANK ANDERSON, all citizens of the United States, and residents of Chicago, county of Cook, and State of Illinois, have invented certain new and useful Improvements in Cosmetic-Powder Dispensers, of which the following is a specification.

10 The present invention relates to powder holders and dispensers of the nature known under the name of "vanity cases" and the like.

15 The invention comprehends the providing of means for use with loose powder, preferably of cosmetic properties, which may be dispensed in economic quantities and in an efficient manner. Cosmetic powder in block or cake forms usually has gritty substances 20 which are objectionable and injurious to the users. This invention uses loose powder entirely free of gritty and similar particles and the powder may be dispensed in small amounts as needed. The term powder as 25 used herein we wish to be understood as including such cosmetic as face powder, rouge, and other similar material.

An object of the invention is to provide 30 a conveyor, preferably in the form of an endless belt or the like, which extends into the powder compartment of the device and into intimate contact with the powder, and which, also, can travel to the exterior of the compartment to carry adhering particles of 35 powder to the exterior for ready access thereto by the user of the device. The carrier is of such material that the powder will adhere readily thereto and be carried by the conveyor, when caused to travel, so that 40 the powder may be fed to the exterior of the compartment for removal therefrom by the user, preferably by the use of a puff or the like. The travel of the conveyor is preferably effected by tractive force applied by 45 the user, as by the fingers of the user, or by the puff, the latter being preferable.

Another object of the device is to provide 50 a carrier for the conveyor, which may be readily detachably located in place, the compartment being normally closed with a cap or cover having an opening in which the carrier may be removably secured. The carrier, in a way, acts as a closure for the opening so as to prevent escape of the powder 55 and at the same time hold the conveyor in

proper operative relation with the powder and the exterior for the dispensing of the powder. The carrier is preferably of resilient material and of a shape so that tension may be impressed and maintained upon the 60 carrier as well as to press the inner portion of the conveyor against the powder in the compartment of the device so that that part of the conveyor will be constantly in contact with the powder. 65

Other objects, capabilities and advantages are comprehended by the invention as will later appear and are inherently possessed by the invention.

In the drawing illustrating two embodiments of the invention, Figure 1 is a plan view of a vanity case, opened, constructed in accordance with the invention; Figure 2 is a transverse sectional view of the same; Figure 3 is a top plan view of the powder containing part of the device; Figure 4 is a similar view of a modified form; and, Figure 5 is a fragmentary transverse sectional view of the device shown in Figure 4 and taken in a plane represented by line 5—5 of Figure 4. 70 75 80

Referring more particularly to the drawings, the embodiment selected to illustrate the invention is shown therein as comprising a powder holding compartment or body 1 85 to which is hinged, by means of a hinge 2, a closing cover 3 in which may be located the usual mirror 4, the cover 3 being capable of a sliding fit over the outer rim of the body portion 1. 90

Within the compartment 5 of the body portion 1, may be slidably fitted a cap or closure member 6, preferably of sheet metal, and having the rim 7 slidably fitting within the outer rim 8 of the body portion 1. The 95 compartment 5 is comprised between the body portion 1 and the cover member 6, forming a space or chamber for the holding of loose powder of cosmetic properties or the like. The face of the cover 6 is provided with an opening 9, preferably of rectangular form, although other shapes may be had if desired, the sides of this opening 9 being provided with inwardly extending flanges 10 and 11 at the ends of the opening 9 and with 105 side flanges 12 and 13, as clearly shown in Figures 2 and 3 of the drawings.

Within the opening 9 is located a carrier member 14 preferably of sheet metal and constructed from a strip of metal bent 110

in the form of a double-U with the free ends 15 and 16 of this member overlapping each other as clearly shown in Figure 2 of the drawing. The material of this member is preferably resilient so that the ends 15 and 16 normally tend to separate from each other. For holding the carrier in place, holding members or elements 19 and 20, in the form of cross pins are provided, 5 these pins extending through alined openings or perforations provided in the flanges 12 and 13 and through the bends at the ends of the carrier. At the side edges of the carrier 14 may also be provided guiding flanges 21 and 22 which perform the 10 function of guiding and maintaining in position an endless conveyor carried by the carrier.

Upon the carrier is carried an endless conveyor or belt 23 passing between the flanges 21 and 22 and over the outer and inner surface portions 24 and 25 of the carrier, the resilience of the carrier, particularly at the open end thereof, tending to impose a tension upon the belt or conveyor 23 and also, by means of the resilient end 15, continually forcing the inner bent portion toward the bottom of the compartment 5 and against whatever powder may be located therein. The belt portions at the ends of the carrier pass close to the flanges 10 and 11 so as to substantially close the opening 9 against any escape of powder therethrough to the exterior of the device. The belt is capable of sliding or traveling about the carrier by applying pressure to the outer surface portion of the carrier and in a direction downwardly as viewed in Figure 2 of the drawing. The inner portion of 20 the belt which is intimately in contact with the powder in the compartment 5, will carry adhering particles of the powder to the exterior of the compartment 5 where the powder may be removed by the user by a puff or the like. When it is desired to fill the compartment 5 the cover member 6, together with the carrier and connected parts may be removed as a unit and a suitable amount of powder placed in the compartment 50 5 and the unit 6 replaced in the body portion 1. If it be desired to remove the carrier, the unit 6 may be removed as above described when filling the powder, and the pins 10 and 20 may then be withdrawn and the carrier, together with the belt, may be removed as a whole.

In Figures 4 and 5, is shown a modification in which the flanges 12 and 13 are provided with indentations 27 and the flanges 60 21 and 22 of the carrier are provided with projections 28 and 29 registering with and capable of snapping into the indentations 26 and 27, the flanges 28 and 29 being sufficiently resilient for this purpose. It will be seen that the carrier may be forced into

the opening 9 until the projections 28 and 29 snap into the indentations 26 and 27, a reverse operation effecting a removal of the carrier in a similar manner. In other respects the modified construction is the same 70 as that described with reference to Figures 1, 2 and 3.

In the use of the device the compartment 5 contains a suitable amount of cosmetic powder free of gritty and similar materials. 75 In use the carrier member 14 resiliently presses an inner portion of the belt in intimate contact with the powder. The user may then apply with the fingers, but preferably with a puff on the outer surface of 80 the belt and in a longitudinal direction thereof, sufficient force to cause the belt to travel around the carrier, the inner portion of the carrier carrying adhering particles of powder to the exterior of the compartment 85 where the same may be accessible to the user and removed from the outer portion of the belt by the powder puff. The transferred particles of powder on the puff may then be used in the usual manner. In 90 this way the powder is dispensed in an economical and efficient manner.

Having thus described our invention, we claim:

1. A powder holder capable of use as a 95 vanity case, comprising a body portion for containing a powder, an endless powder conveyor movably arranged in said case and extending into the powder space of the body portion for contact with the powder, said 100 conveyor being capable of carrying adhering powder thereon to a point where the powder may be removed from the conveyor by the application of a powder puff or the like.

2. A powder holder capable of use as a vanity case, comprising a powder holding compartment, a conveyor carrier in said compartment, an endless conveyor on the carrier and having a portion thereof contacting with the powder in said compartment and a portion thereof exposed to the exterior of the compartment, said conveyor being movable to carry powder adhering thereto to the exterior of the compartment 110 for access thereto by the user.

3. A holder for containing loose cosmetic powder, comprising a powder chamber, a conveyor supporting means in said chamber, an endless conveyor carried by said means and dipping into said powder whereby the powder may adhere to said conveyor and be carried thereby when the conveyor is moved to present the conveyed powder in accessible position for use by the user.

4. A vanity case comprising an apertured compartment for containing loose cosmetic powder, a traveling member dipping in the powder within said compartment and arranged to form a closure for the aperture,

said member being capable of carrying some of the powder to the exterior of the compartment for access thereof by the user, and means within the compartment for supporting the traveling member in said compartment whereby the member may be made to travel by the user.

5. A loose powder dispensing device, comprising a compartment for containing loose cosmetic powder, the top wall of said compartment being provided with an opening, a conveyor carrier located in said opening and having means for detachably holding said carrier in place, an endless conveyor slidably carried by said carrier and having a part exposed at the exterior of the compartment in said opening and another part of the conveyor located in the compartment and in contact with the powder therein, whereby when the conveyor is caused to slide particles of powder adhering to the conveyor may be brought to the exterior of the compartment at said opening for access thereto by the user of the device.

6. A vanity case for loose powder, comprising a powder containing body, a closing member for normally closing the compartment, said member being provided with an opening, a resilient conveyor carrier located in said opening, means for removably holding said carrier in place, an endless conveyor carried by said carrier and capable of passing through the powder in the compartment and over the carrier in said opening for exposing the surface of the conveyor to the exterior of the compartment for access to the powder carried thereby, said carrier normally imposing a tension on the conveyor to maintain the same taut and to hold the portion of the conveyor in the compartment in intimate contact with the powder therein.

In witness whereof, we hereunto subscribe our names to this specification.

ROY M. WARBERG.
BERNHARD ANDERSON.
FRANK ANDERSON.
